UNITED STATES PATENT OFFICE.

CLIFFORD DUDLEY BABCOCK, OF NEW YORK, N. Y., ASSIGNOR OF ONE-HALF TO JOHN NEILSON, OF NEW YORK, N. Y.

IONIZED-CHAMBER DEVICE.

1,222,916.

Specification of Letters Patent.

Patented Apr. 17, 1917.

Application filed October 24, 1916. Serial No. 127,335.

To all whom it may concern:

Be it known that I, CLIFFORD DUDLEY BABCOCK, a citizen of the United States, and resident of New York, borough of Manhattan, in the county and State of New York, have invented certain new and useful Improvements in Ionized-Chamber Devices, of which the following is a specification.

This invention is an improvement in ionized chamber devices and more particularly those types adapted for use as detectors, indicators, amplifiers, repeaters, relays or other similar or analogous devices for detecting, amplifying, repeating, relay-
ing or indicating electrical currents, or variations of direction or steadiness of flow thereof.

The main objects of my invention are to reduce the number of lead wires sealed through the walls of the bulb, cylinder, or other envelop; to save the cost of the separate condenser commonly used in connection with such devices; to provide means for varying the capacity of the condenser; to provide a simple and efficient means for adjusting the distances between the elements within the envelop after it has been pumped out and sealed off; and to reduce the number of pieces of apparatus necessary in the construction and installation of systems or plants in which such devices may be used.

Various other important objects of my invention and advantages of my improved construction will be pointed out more particularly hereinafter in connection with the detailed description of one embodiment thereof. In the accompanying drawings,

Figure 1 is a central longitudinal section of a device embodying my invention, certain of the parts being shown slightly in perspective, and a wiring diagram illustrating a wireless receiving system in which the device may be employed; and
Fig. 2 is a transverse section on the line 2-2 of Fig. 1.

Merely for purposes of illustration, I have shown my improved device in connection with circuits similar in most respects to those illustrated in the De Forest Patent No. 879,532, granted February 18th, 1908. In this wiring diagram, the elevated conductor V has earth connections at E and a

primary I₁ of a transformer M. The secondary I₂ of the transformer forms part 55 of the tuned receiving circuit I₂C in which C represents an adjustable condenser. The sealed envelop D incloses an electrode F in the form of a filament connected in series with a battery A whereby the filament may 60 be heated. Within the sealed envelop D are also the input electrode or grid a and the output electrode or plate b. The plate is connected through a telephone or other signal indicating device T and a battery B 65 to one terminal of the filament. The other terminal of the filament is directly connected to one terminal of the secondary I₂ of the transformer while the other terminal of the input electrode is inductively connected 70 to the other terminal of said secondary.

I wish it particularly understood that this arrangement of circuits forms no portion of my invention and is shown and described merely to illustrate one system in which one 75 form of my device may be employed. Neither do I claim any novelty in the particular construction or relative arrangement of the three electrodes a, b, and F.

As the important feature of my invention, I utilize a wall of the envelop or chamber as the dielectric of a condenser which is connected in series with one of the electrodes within the chamber. In the specific form illustrated, the envelop is of tubular 80 form and uniform in cross section for a considerable length. The peripheral wall may have any curve such as elliptical or oval, but is preferably cylindrical.

Inside of the chamber, I mount a sleeve 90 11 of metal or other suitable conducting material and preferably of an external diameter substantially equal to the internal diameter of the peripheral wall 10. It may be split lengthwise or otherwise designed so 95 as to adapt it to slight variations in the diameter of the envelop wall and to allow of its being held in position by friction fit.

Outside of the envelop wall, I provide a second sleeve 12 which is also of metal or 100 other suitable conducting material and of an internal diameter substantially equal to the external diameter of the envelop wall 10. This external sleeve or tube 12 may be clamped or otherwise effectively secured to 105 the envelop wall and may, if desired, be

held against longitudinal movement, although in practice it is preferable to make it also of a friction fit so that it may, if desired, be adjusted lengthwise of the envelop wall.

The two sleeves, tubes or plates, 11 and 12 are thus separated by the thin envelop wall of insulating material and constitute an adjustable condenser. The inner plate or wall 10 of the condenser is connected to the grid *a* by a lead wire 13 while the outer plate or wall is connected to the transformer. This condenser, formed by the inner and outer sleeves and the envelop wall, is thus in the 15 circuit between the grid *a* and the transformer and permits the omission of the condenser C' of the De Forest patent above referred to.

By means of this construction, the capacity 20 of the condenser may be varied by varying the areas of the opposed surfaces of the two sleeves 11 and 12. This adjustment or variation may be secured by sliding the outer sleeve 12 lengthwise of the envelop 25 wall or by giving the envelop or chamber a sudden jar in the direction of its major axis, whereby the inner sleeve may be caused to slip endwise a limited distance within the envelop. It will be noted that the inner 30 sleeve is somewhat shorter than the cylindrical portion of the peripheral wall of the envelop to permit such endwise sliding.

Although the grid or input electrode *a* may be supported from the stem or other 35 part of the envelop, and may be connected to the inner sleeve or plate of the condenser by flexible lead wires, I preferably make the leads comparatively stiff and utilize the sleeve as a direct support for the grid. By 40 this arrangement, the grid may be placed in approximately the desired position in respect to the other electrodes before the envelop is pumped out and sealed, and after the pumping and sealing operations have 45 been completed, the device may be connected in circuit by flexible lead wires and may be given sudden jars in the direction of its major axis to slide the internal sleeve endwise in either direction, to vary the distance 50 between the input electrode *a* and the other electrodes, or to vary its position in respect to them.

The facility with which the relative positions 55 of the electrodes may be adjusted after the device is sealed, and the facility with which the capacity of the condenser may be adjusted, enables me to secure, in a measure, the desired tuning and, in part, avoid the necessity for the use of the usual synto- 60 nizing devices. The presence of the relatively large mass of the inner sleeve 11 is in many cases an additional advantage, as the metal tends to preserve a more stable condition within the bulb and thereby increases 65 the useful life thereof.

It is evident that the outer sleeve 12 may be in the form of a clamp secured to a suitable base so that the envelop will be carried by and preferably adjustable within said support. This will obviate the necessity for 70 providing the usual threading base and will permit the contacts for heating the filament to be made by any other suitable means. The leads from the filament may merely extend through the wall of the envelop as is 75 shown for the lead from the plate *b*.

Having thus described my invention, what I claim as new and desire to secure by Letters Patent is:

1. An ionized chamber device comprising 80 a sealed vessel, an input electrode, an output electrode, an electrode adapted to be heated, a condenser having the spaced plates thereof upon opposite sides of and spaced by a wall of the vessel, and connections within said vessel between one of said electrodes and the inner plate.

2. An ionized chamber device including a sealed vessel, two electrodes inclosed within 90 said vessel, means for heating one of said electrodes, and a condenser including spaced plates upon opposite sides of a wall of the vessel, the plate within the vessel being connected to the other electrode.

3. An ionized chamber device including a 95 sealed chamber, spaced condenser plates upon opposite sides of a wall of the chamber, and a plurality of electrodes within the chamber, one of said electrodes being connected solely to the inner condenser plate. 100

4. An ionized chamber device including a tubular vessel, a conductor within said vessel closely adjacent to a wall thereof, a separate conductor outside of said vessel and closely adjacent to said wall opposite to said 105 first mentioned conductor, an electrode within said vessel and connected to said first mentioned conductor, and a second electrode within said vessel and having a lead extending through the wall of the vessel. 110

5. An ionized chamber device including a tubular vessel, a condenser plate within said vessel closely adjacent to a wall thereof, a separate condenser plate outside of said vessel and closely adjacent to said wall opposite 115 to said first mentioned condenser plate, an electrode within said vessel and connected to said first mentioned condenser plate, and a second electrode within said vessel and having a lead extending through the wall of the 120 vessel.

6. An ionized chamber device including a tubular vessel, a condenser plate within said vessel closely adjacent to a wall thereof, a separate condenser plate outside of said vessel and closely adjacent to said wall opposite to said first mentioned condenser plate, an electrode within said vessel and connected to said first mentioned condenser plate, and a second electrode within said vessel and hav- 125 130

ing a lead extending through the wall of the vessel, one of said plates being adjustable in its own plane in respect to the other.

7. An ionized chamber device, including a sealed chamber, a pair of electrodes inclosed within said chamber, means for heating one of said electrodes, a third electrode within said chamber, and a support for said last mentioned electrode having frictional engagement with the wall of the chamber and adjustable to vary the position of said last mentioned electrode in respect to the other two.

8. An ionized chamber device including a sealed vessel, an electrode inclosed therein and having a lead extending through the wall thereof, a second electrode within said vessel and in operative relationship to the first mentioned electrode, and a support for said second mentioned electrode bodily shiftable with said second mentioned electrode.

9. An ionized chamber device including a sealed vessel, an electrode inclosed therein and having a lead extending through the wall thereof, a second electrode within said vessel and in operative relationship to the first mentioned electrode, and a support for said second mentioned electrode bodily shiftable with said second mentioned electrode by a jarring of the device in the direction of the permissible movement of said support.

10. An ionized chamber device including a chamber, a sleeve having frictional engagement with the inner wall thereof and movable axially in respect thereto, an electrode having fixed relationship to the wall of said chamber, and a second electrode carried by said sleeve.

11. An ionized chamber device including a chamber, a sleeve having frictional engagement with the inner wall thereof and movable axially in respect thereto, an electrode having fixed relationship to the wall of said chamber, a second electrode carried by said sleeve, and a second sleeve encircling said chamber and, together with said first mentioned sleeve and the wall of the chamber, forming a condenser.

12. A combined ionized chamber device and condenser, comprising a chamber having a wall of dielectric material, condenser plates upon opposite surfaces of said wall, and a plurality of electrodes within the chamber, one of said electrodes being connected to the inner plate of the condenser.

13. An ionized chamber device comprising

a sealed chamber, having a wall of dielectric material, plates upon opposite surfaces of said wall to constitute a condenser, one of said plates being adjustable to vary the area of opposed surfaces, a plurality of electrodes within said chamber, means for heating one of said electrodes, and connections between the inner of said electrodes and the inner plate of the condenser.

14. An ionized chamber device comprising a sealed chamber, having a wall of dielectric material, plates upon opposite surfaces of said wall to constitute a condenser, one of said plates being adjustable to vary the area of opposed surfaces, a plurality of electrodes within said chamber, and means for ionizing the space between said electrodes.

15. A combined condenser and ionized chamber device, including a tubular vessel having a glass peripheral wall, a pair of sleeves concentric with said wall and spaced apart by said wall, an electrode within said vessel, means for heating said electrode, and a second electrode within said vessel and operatively connected to the inner sleeve.

16. A combined condenser and ionized chamber device, including a tubular vessel having a glass peripheral wall, a pair of sleeves concentric with said wall and spaced apart by said wall, an electrode within said vessel, means for heating said electrode, and a second electrode within said vessel and operatively connected to the inner sleeve, one of said sleeves being axially adjustable in respect to the other.

17. A combined condenser and ionized chamber device, including a tubular vessel having a glass peripheral wall, a pair of sleeves concentric with said wall and spaced apart by said wall, an electrode within said vessel, means for heating said electrodes, and a second electrode within said vessel and operatively connected to the inner sleeve, said inner sleeve being adjustable axially to vary the relative positions of said electrodes.

18. An ionized chamber device, including a vessel having a plurality of electrodes therein, a condenser including a pair of plates upon opposite sides of a wall of said vessel, and connections between one of said electrodes and one of said plates.

Signed at New York, in the county of New York and State of New York, this 20th day of October, A. D. 1916.

CLIFFORD DUDLEY BABCOCK.
